PROJECTILE

Edgar William Brandt, Geneva, Switzerland, assignor to Anstalt für die Entwicklung von Erfundenen und gewerblichen Anwendungen "Energa," Vaduz, Liechtenstein, a corporation of Liechtenstein

Application July 11, 1947, Serial No. 760,423
In Switzerland November 9, 1946

2 Claims. (Cl. 102—50)

1

This invention relates to projectiles and more particularly to hollow charge perforating projectiles.

Amongst novel anti-tank weapons utilised during the course of the war, so-called hollow charge devices revealed remarkable possibilities.

Nevertheless, these hastily developed devices still did not possess the essential qualities required for present-day armament; they had neither optimum performance relatively to their weight, nor the desired standard of safety, nor the practical possibilities of utilisation which research for better technical and constructional arrangements, as well as experimentation, could give them.

The functioning of hitherto designed hollow charge perforating devices has been previously expounded and described, and may be summed up as follows:

An explosive charge, acting on a preferably metallic cone or hood having a large surface and slight thickness, closes and transforms said hood into a solid core of much smaller diameter which is thus projected at high speed by said explosive charge. Considerable energy, previously collected by this means on a large surface, is in this manner concentrated to act against the armour over a much smaller surface.

Now, if the speed imparted to the core by the explosive charge is of the order of 2000 metres per second, and if this core in formation has to cover a certain distance before reaching the armour, the gases partially liberated at that moment from the mask and from the hood flow forwards towards the target with a very much greater velocity and may, on the one hand, prevent the correct closing of the hood and, on the other, constitute between the core and the armour a protective cushion which greatly reduces the perforating power.

In the design of the hollow charge projectile forming the subject of the present invention, the increase in perforating power relatively to that obtained in prior designs results from structural dispositions and proportions by which the explosive power determines and develops an essential supplementary effect not hitherto analysed or described, but nevertheless capable of supplying the main result.

These novel dispositions and proportions, as will hereinafter be fully described, actually ensure the formation and projection of a jet issuing from the interior of the core and thrown forward of the latter with such velocity that it reaches the armour at a useful distance, without the gases of the explosive charge being able to diminish the effect thereof. This result constitutes an effective reply to the protective means that have been designed to equip tanks, by providing on the exterior of their jackets a light covering or pre-armour intended to effect the bursting of hollow charge devices sufficiently ahead of the principal

2

armour so as substantially to reduce the useful effect thereof.

Now, it is particularly important to be able to provide combatant units, particularly front line formations, with anti-tank weapons which are at one and the same time, light, simple, powerful, and dependable, capable of effective action against armoured fighting vehicles of all classes, even those equipped with the protective devices hereinbefore referred to.

In order to achieve this object, it is therefore convenient to have available very high performance equipments possessing the essential technical characteristics.

15 The hollow charge anti-tank projectile of the present invention is of the type comprising an explosive charge of a thickness decreasing from the apex of the hood to become almost zero at the base, and is characterized in that said charge is of conical shape externally for about two-thirds of its height and then substantially cylindrical, the height of the conical portion of said charge being comprised between 80% and 120% of the height of the perforating hood.

20 Experience has shown that the perforating efficiency of a projectile complying with the foregoing feature is far greater than that of any other known hollow charge projectile. The explosive charge, burning from the rear towards the front outside the hood applies to the whole surface of said hood a thrust which at the same time causes its projection forwards and its progressive closing from the rear to the front along its longitudinal axis. Under the powerful action 25 of the explosive, the wall of the hood is projected with considerable velocity from the periphery towards the axial centre; the material of said hood, which is of great density (for example mild steel) and has a high coefficient of elongation and 30 therefore great malleability, is thrown in symmetrical fashion and from the rear (apex of the hood) towards the front (base of the hood) with such velocity that, under the influence of the considerable pressure developed, part of the internal and central thickness of the material 35 forming the hood is projected from the interior and from the rear ahead of the mass, in the form of a liquid jet, with extremely great velocity.

35 This velocity is liable to exceed even that of the explosive deflagration proper, i. e. 7000 to 40 8000 metres per second.

45 By virtue of the fantastic velocity of this jet, the perforating effect that it supplies is greatly superior to that of which the core proper is capable, the latter merely following the jet which has preceded it. With the proportions and 50 dispositions forming the subject of the present invention, the thickness of steel armour thus perforated reaches, and may exceed even twice the 55 diameter of the hood and of the explosive charge.

60 The considerable instantaneous work and the enormous pressure produced on the armour by

3

this perforating jet result in a likewise considerable heating, which is as high as the melting temperature of the material perforated.

The transmission of fire between the fuze head and the detonator placed in the charge in rear of the apex of the hood is ensured by waves. The presence of any transmission system of solid and inert matter, placed axially inside the projectile between the fuze head and the apex of the hood, would through its presence in weight and volume greatly hinder the aforescribed phenomenon, and would cause a great diminution of the desired effect and perforating power.

Not only do the given structural dispositions and proportions ensure a greater perforating effect, but the latter is conserved over a substantially greater distance than in the case of previous designs.

The projectile of the present invention is further characterized in that the distance between the front of the fuze-head and the detonator placed inside the charge is at least equal to twice the height of the hood from its apex to its base, and in that said distance corresponds to that necessary for obtaining the optimum effect of the perforating core on the target, plus a supplementary distance which, taking into account the speed of the projectile, corresponds to the path which, from the moment of impact, the perforating core still travels towards the target during the time of operation.

The projectile of the present invention complies with the required conditions by reason of its considerable perforating power relatively to its weight and calibre, its ease of firing, and its great accuracy. Furthermore, it has the advantage of possessing a ballistic form of least resistance, perfect stability during the trajectory, and, relatively to the speed of projection, maximum range.

Said projectile, having thin walls preferably of light metal, does not throw off splinters which are dangerous to the firer when it acts on the target, even at short range. Thus, in the case of the type designed for rifle propulsion, the perforating hood constitutes in weight, apart from the explosive charge, the principal part of the device.

In accordance with another feature of the invention, the front of said head-fuze and the internal safety device of the grenade are disposed, in relation to the base of the hood, symmetrically and at substantially equal distances from said base.

The arrangement and proportions of the devices permit operation, even at very high incidence, while giving the firer the maximum safety. A delayed arming device interposed between the fuze and the detonator prevents any premature transmission of fire to the explosive charge and is displaced after the projectile has been fired.

The safety devices employed during handling and safety devices guarding against shock are important, because the projectile must be able to be transported and utilised in any circumstances and in any terrain.

With a view to storage and transportation, it is often required that projectiles should be capable of complete removal of the detonator. According to still a further feature of the invention, a detachable detonator is provided, which is adapted to be inserted into the explosive charge through the base of the projectile, behind a safety device designed to prevent any premature transmission of fire when the projectile is equipped with its head fuze.

4

In a projectile of the type forming the subject of the invention and comprising a hollow charge provided at the front with a metallic hood, it is difficult to envisage the fitting of the detonator through the front. Provision is therefore made for the detachable detonator to be housed in a small, preferably cylindrical, cake of explosive, which is adapted to be inserted into a corresponding cavity provided in the rear portion of the explosive charge of the projectile. To this end, the base portion of the projectile comprises an aperture which is hermetically sealed by means of a safety stopper, which can be locked and immobilised by screwing the tail on the projectile.

The projectile of the present invention may be designed:

1. As a rifle grenade; it is then provided with a tubular vaned tail which caps the launching attachment fitting the end of the rifle barrel.

2. As a projectile intended to be launched from a smooth bore barrel; the outer wall being reinforced, particularly in the conical portion, to withstand the pressure of the propulsion gases, it then comprises at the rear a cartridge containing the propulsive charge; vanes are mounted either on the charge carrier tail or on the rear of the body of the projectile.

3. As a projectile fitting into a tubular case carrying the propulsive charge, or as a projectile provided with a self-propelled vaned device for firing without recoil from an appropriate launching tube.

4. As an anti-tank aircraft projectile; in this case, on being released from the aircraft, suitable vaning, for example deploying over a greater diameter than that of the projectile, ensures its stability; the vaning may also cause the gyration of the projectile and, in consequence, the arming of the internal safety device at a desired distance.

Other advantages and features of the invention will be apparent from the following description taken in conjunction with the accompanying drawings which illustrate diagrammatically and by way of example various embodiments thereof, and in which:

Fig. 1 illustrates in elevation and partial longitudinal section one embodiment;

Fig. 2 illustrates diagrammatically the formation of the core under the action of the deflagration of the explosive charge;

Fig. 3 is a plan view of the phenomenon illustrated in Fig. 2;

Fig. 4 illustrates, in elevation and partial longitudinal section a perforating hollow charge projectile provided with a detachable detonator;

Figs. 5 and 6 show respectively, in elevation, embodiments of projectiles intended to be fired from smooth bore barrels;

Fig. 7 shows, in exterior view, a projectile fitted into a rear tubular case carrying the explosive charge;

Fig. 8 illustrates in elevation a projectile provided with a self-propelling device;

Fig. 9 is an exterior view, partly in section, of an anti-tank aircraft projectile provided with vanes adapted to deploy over a greater diameter than that of the projectile.

The projectile illustrated in Fig. 1 consists of a body 1 provided at the front with a conical head 2, and at the rear with a tail 3 provided with vanes 4.

The body 1 is formed of a jacket 5 housing the explosive charge formed by two superimposed masses 6 and 7. The upper mass 6 is the main

charge and consists of high explosive, which may be either compressed or cast, and the lower mass 7 or relay charge preferably consists of compressed pulverulent explosive.

On its front face, the mass 6 has a deep conical cavity 8 which opens out from the rear towards the front. Against the walls of this cavity is applied a metallic hood or cone 9 immobilized in position by a collar or mask 10 fixed on the shell 5 below the conical head 2. The explosive charge 6-7, which is thus of decreasing thickness from the apex of the hood and becomes almost zero at the base of the latter, is conical externally over about two-thirds of its height and then substantially cylindrical, the height of the conical portion of said charge being equal to that of the perforating hood or approximating thereto.

The collar or mask 10 has at its base an outer diameter substantially equal to that of the base of the perforating hood 9; the internal oblique face 11 of said mask being of a height at least equal to its width in section 12, it forms with the inner wall of the perforating hood 9 an angle α of at least 90° .

A member 13 caps the mask 10, forming a support for the crimping of the jacket 5 on the conical head 2 provided with the fuze 14, and is extended inside said fuze-carrying head.

This general arrangement and the proportions allowed, enable a minimum external calibre, relatively to the diameter of the perforating hood, to be obtained, and thus minimum weight in relation to power, as well as easy mounting of the component parts.

A detonator 15 is housed preferably in the mass 7 of pulverulent explosive, which acts as a relay between said detonator 15 and the high explosive 6. Fire is transmitted by waves from the fuze 14 to the detonator 15.

A wedging washer 37, preferably of cork, is provided to immobilise the detonator 15.

Fig. 2 illustrates the operation and effect obtained with the novel arrangement of Fig. 1.

The explosive charge, deflagrating from the rear towards the front outside the hood 9, which is made of a material of sufficient density (such as mild steel) and having a high coefficient of elongation and therefore great malleability, applies to the whole of the surface of said hood a thrust which effects the concentration and projection of the material constituting said hood:

1. Projection to the front of the whole of the material of the hood in accordance with the arrows a' , b' , and so on.

2. Concentration of said material towards the longitudinal axis of the hood, following the arrows a , b , and so on.

It is noted that the resistance that the material constituting the hood, which is beaten out and driven by the explosive charge, can offer is negligible in relation to the power of action of said charge.

Now, if the speed of projection a' , b' , or, respectively, any other speed x' , along the longitudinal axis is already relatively great (about 2000 metres per second), the speed x , or respectively any other speed Vx , acquired transversely by the material of said hood is already decidedly greater, and at least double.

It will be seen, moreover, that the transverse components of the speeds Va and Vx , which are equal, oppose one another; so that the convergence towards the axis of the material of the hood will take place according to a resultant V at extremely high speed.

Moreover, the plan view (Fig. 3) shows that the material is projected in converging manner towards the centre (longitudinal axis of the hood). Now the meeting of said matter takes place from the rear towards the front on this centre, and the high speed at which it takes place, as well as the irresistible pressure developed, cause the projection of a jet ahead of the central portion of the closed hood, the speed of said jet accelerating to reach the value W which is considerably higher still. The arrangements and proportions of the projectile of the present invention ensure this jet of optimum formation and remarkable effectiveness. The speed of said jet is in fact liable to exceed to a marked degree that of the explosive deflagration proper, which itself attains a speed of 7000 to 8000 metres per second.

It is clear from Fig. 1 that the distance between the front of the fuze head 14 and the detonator 15 placed inside the charge is at least equal to twice the height of the perforating hood 9 from its apex to its base.

In addition, the total length and the diameter of the fuze head 14 are equal and inferior respectively to twice the length and diameter of the transmitter cap 16. The total weight given by the assembly of parts constituting said fuze is thus reduced to less than four times the weight of said cap 16.

The front fuze head 14 and the internal safety device 17 of the grenade (Fig. 1) are, in relation to the base of the perforating hood, disposed symmetrically and at substantially equal distances from said base; this enables the projectile to be given the aerodynamic shape compatible with stability, minimum resistance, and maximum range.

The fuze carrier member 2 and the fuze 14 are combined in such manner that, in consequence of the ready deformation of the fuze carrier 2, the fuze 14 acts instantaneously on impact through being driven in and by inertia, without any reduction of speed or the weight of the projectile having to intervene in this operation.

This result is all the better for the fact that, on the one hand, the fuze body is shorter, more rigid, and less deformable by shock, and that, on the other hand, the fuze carrier has less resistance to the shock of impact.

The apex of the hood 9 is situated towards the centre of the total length of the projectile (Fig. 1).

The outer jacket 5 of the explosive charge 6-7 and the base 18 carrying at the rear the tubular propulsion tail 3 provided with the vanes 4 are assembled over the height of said base and fixed in the interior of the latter by means of a seating 19 in the form of a recess, this seating being obtained by means of a washer 20 domed in the first place and, when straightened by pressure, giving the desired expansion and ensuring the maintenance of the fit.

This method of mounting is extremely simple and at the same time very strong; it enables the weight of the affected members to be reduced to the minimum, and thus contributes towards obtaining a particularly light projectile.

The base portion 18, placed in rear of the explosive charge, covers peripherally, over its entire height, the small cake of explosive 7 (Fig. 1), and the diameter of the latter is about half that of the principal cake 6.

The weight of the explosive charge 6-7 as a whole is substantially equal to half the total weight of the projectile.

The vaning 4 is composed of a series of thin

vanes 21 bedded in the thickness of the wall 22 of the tubular guiding tail, these vanes projecting to the rear of said tail and forming a vaning of a height substantially less than its diameter.

This disposition of multiple vanes renders it possible, with the minimum aerodynamic resistance, to obtain an optimum stabilisation effect with a minimum surface and weight of material, the minimum weight of the vaning at a great distance from the centre of gravity effectively intervening to increase the stability of the projectile.

In the example illustrated in Fig. 1 of a projectile equipped in accordance with the features of the invention, the base of the perforating hood supports, on firing, the inertia effect of the whole of the front portion (mask, ogival head, fuze). Use is thus made of the very great strength at the base of the hood and of the cake of explosive, which thus assure the whole assembly a remarkable solidity.

Finally, the proportions allowed enable a projectile to be designed the centre of gravity of which is substantially midway in its total length.

The projectile illustrated in Fig. 4 is similar to that illustrated in Fig. 1, but comprises a detachable detonator housed in a small cake of compressed explosive 27, in which is provided a cavity 28 corresponding to the external shape of the detonator 15. A cylindrically shaped cavity 29 is moreover provided in the lower mass of compressed pulverulent explosive 7, the diameter of said cavity corresponding exactly to that of the cake 27.

The safety device 17 may either be integral with the detachable detonator, or be independent and be permanently mounted in the housing 30 provided for that purpose in the upper mass of high explosive 6.

An aperture 31, of the same diameter as the cavity 29, is reserved in the base 18 of the projectile to permit the introduction of the detonator into said cavity 29. The aperture 31 is provided with a safety stopper 32, which is locked and immobilised by screwing on to the base the tail 3.

In this particular case, provision has been made for a stronger mounting for the vanes than in the device illustrated in Fig. 1. The tube 22 of the tail 3 comprises, near its rear end, a circular countersunk portion 33 edged on the one hand, at the front, by a re-entrant bevelled rim 34 and, at the rear, by a circular flange 35. The vanes 21 are fashioned in sets of two, cut from the same sheet of metal, and have between them a portion in the shape of a cylindrical segment 36, which engages in the circular countersunk portion 33, after which the flange 35 is fitted over the vanes, which are thus immobilised on the tube 22.

The projectiles illustrated in Figs. 5 and 6 are intended to be fired from a smooth bore barrel; they comprise at the rear a cartridge 23 containing the propulsive charge. Vaning 4 is mounted either on the charge carrier tail 3 (Fig. 6), or on the rear of the projectile (Fig. 5).

The projectile illustrated in Fig. 7 is fitted into a rear tube 24 carrying the propulsive charge 23.

The projectile may also be provided with a vaned self-propulsion device 25 for firing without recoil from an appropriate launching tube (Fig. 8).

In the event of the projectile of the invention

constituting an anti-tank aerial bomb (Fig. 9), it comprises suitable vaning 26 which, on release from the aircraft, is adapted to unfold in accordance with 26', for example, over a greater diameter than that of the projectile itself, and thus ensures great stability of the latter; it may also cause the gyration of the projectile and, in consequence, the arming of the internal safety device of the latter at a desired distance.

What I claim is:

1. A hollow charge perforating projectile, said projectile comprising: a shell, a high explosive charge in said shell, said high explosive charge being formed with a front cavity, a hood applied against the walls of said cavity and adapted to be transformed by the detonation into a core, a base portion on said shell, a vaned tubular guiding tail mounted at the rear of said base portion, said base portion being formed with an annular inside groove at its rear inside end, said shell and said base portion engaging mutually over the height of the base portion, and a washer engaging the back part of said shell and being adapted to be forced during mounting into said groove to set together the shell with the base portion, in order to ensure the tightness between them.

2. A hollow charge perforating projectile, said projectile comprising: a shell, a high explosive charge in said shell, said high explosive charge being formed with a front cavity, a hood applied against the walls of said cavity and adapted to be transformed by the detonation into a core, a base portion on said shell, a vaned tubular guiding tail mounted at the rear of said base portion, said base portion being formed with an annular inside groove at its rear inside end, said shell and said base portion engaging mutually over the height of the base portion, and a washer engaging the back part of said shell and being adapted to be forced during mounting into said groove to set together the shell with the base portion, in order to ensure the tightness between them, said high explosive charge comprising a large cake and a small cake of explosive, said small cake being placed at the rear of the large cake, said base portion covering peripherally said small cake of high explosive for its entire height.
